Application December 29, 1944, Serial No. 570,418

7 Claims. (Cl. 230—101)

1

Our invention relates to pumps and, particularly, to self-fractionating oil-diffusion pumps.

In the operation of fractionating diffusion pumps, it has heretofore been customary to provide separate boiler compartments for each pumping stage of the pump, and to circulate the pumping fluid from the various compartments of the pump as the fractions are distilled off.

According to our invention, a self-fractionating pump is provided, utilizing a common boiler for all of the pumping stages. In order to secure the evolution of the various volatiles at different points on the surface of the liquid in the boiler, the boiler is divided into a plurality of cells, and the pumping fluid retarded in the cells until the various volatiles have been evolved. These cells may either be concentric ring-like cells, or may be a plurality of relatively well-like cells provided by a metallic grid structure. The circulation of the oil or other vapor-evolving liquid is retarded by providing relatively restricted openings so disposed that the liquid entering the boiler is first admitted to one group of cells, and then passed to a succeeding group of cells.

In order to separate the various volatiles at the pumping nozzles, independent chimneys are provided for each nozzle or jet, the bottom of the chimneys being extended in proximity with the surface of the liquid in the boiler, and preferably provided with baffles to impede the flow of vapor adjacent to the surface of the liquid in the boiler.

It is an object of our invention to provide a self-fractionating pump, utilizing a common boiler for all pumping stages.

It is a further object of our invention to provide a boiler structure which reduces the turbulence of the boiler liquid.

It is a further object of our invention to provide a boiler structure which will separate out any foreign matter found in the vapor-evolving material.

It is a further object of our invention to provide a boiler structure in which all portions of the vapor-evolving liquid are substantially uniformly heated.

Other objects and advantages of our invention will be apparent in the following detailed description, taken in conjunction with the accompanying drawing, in which:

Figure 1 is a sectional elevation of a pump according to our invention;

Fig. 2 is a partial plan view, showing one method of providing the boiler cells;

Figs. 3 and 4 are fragmentary views, showing a further method of providing the boiler cells.

In an exemplary embodiment of our invention, a multiple-stage pump, herein shown as a two-stage pump for simplicity of illustration, is pro-

2

vided with a pumping chamber 10 having an opening 11 to the space to be evacuated and a discharge opening 12 to any suitable backing pump (not shown). The pumping jets 13 and 14 are herein shown as of the down-draft variety; but, obviously, the invention is applicable to any type of diffusion pump.

The boiler or vapor-evolving compartment 15 of the pump is placed adjacent the bottom of the pump chamber and is divided into a plurality of vapor-evolving cells 16. These vapor-evolving cells 16 may be constructed in a variety of ways.

In the embodiment according to Figures 1 and 2, the cells 16 are constructed of substantially cubical formation by means of a metallic grid-like member 17 inserted in the boiler 15. Preferably, the grid-like member 17 is of such a height as to be normally immersed in the vapor-evolving fluid 18. Suitable passages 19 are provided between the various cells 16 to permit an impeded fluid flow from the outer to the inner cell structures. The cell structures not only retain the fluid 18 until certain volatiles have been evolved, but they further aid the action of the pump by providing settling chambers in which any dirt or foreign matter will be separated out in the cells 16 adjacent the exterior of the pump.

The cell structure further prevents excessive turbulence of the vapor-evolving fluid 18 by preventing random flow of the liquid and separating the liquid into relatively small areas. The metallic nature of the cell-forming bodies 17 also distributes the heat substantially uniformly to all portions of the liquid 18 which further reduces turbulence of the liquid.

It is desirable to conduct the most volatile materials to the jet having the higher pressure, that is, the discharge jet 14; and, accordingly, the chimney 20 supplying vapor to the high-pressure jet 14 is associated with that portion of the boiler surface from which the most volatile materials are evolved. The jet 13 associated with the intake or low-pressure side of the pump would have the least volatile material supplied thereto; and, therefore, the chimney 21 supplying the low-pressure jet 13 is associated with the area of the boiler 15 from which the least volatile materials are evolved.

In order to prevent intermingling or migration of the vapors evolved under the various chimneys 20—21, the bottoms of the chimneys are extended in proximity to the surface of the vapor-evolving liquid 18, preferably being separated by a space of the order of $\frac{1}{8}$ to $\frac{1}{4}$ inch. Additional baffles 22—23 are usually provided to increase the degree of separation or impede the flow of vapor along the surface of the liquid 18.

In the operation of the pump according to our

invention condensate from the various jets 13-14 will be returned to the outside cells 16, where they will be heated and the higher volatiles will be evolved and pass into the chimney 20 connected with the high-pressure jet 14. The liquid stripped of its higher volatiles will pass through the openings 19 to the adjacent cells, where the less high volatile materials will be evolved. The ultimate cells 16 thereby evolve the lower volatile materials which pass through the chimney 21 connected with the low-pressure jet 13, the baffles 22-23 between the chimneys 20-21 serving to prevent intermingling of the lower and higher volatile materials.

In the modification according to Figs. 3 and 4, the cells 16 are provided by means of concentric ring-like baffles 117 which are preferably so connected that the vapor-evolving liquid traverses the rings quite slowly, and preferably so that the liquid must travel substantially the length of the cell before being admitted to the adjacent cell.

For reasons of simplicity, we have shown and described preferred embodiments of our invention; however, it will be apparent to those skilled in the art that changes and modifications can be made therein without departing from the true spirit of our invention or the scope of the appended claims.

We claim as our invention:

1. A vacuum pump comprising a substantially cylindrical pump chamber, a plurality of axially spaced pumping jets in said chamber, a plurality of coaxial vapor passages for delivering vapor to said jets, a common boiler adapted to contain pumping liquid for producing the pumping vapor, means in closely-spaced relation above the level of said liquid for associating the vapor passages with predetermined portions of the surface of the liquid in the boiler said means including a depending baffle for impeding migration of pumping vapor, and means in said boiler for controlling the quality of the vapor evolved in the several portions of the boiler.

2. A vacuum pump comprising a substantially cylindrical pump chamber, a plurality of axially spaced pumping jets in said chamber, a plurality of coaxial vapor passages for delivering vapor to said jets, a common boiler adapted to contain pumping liquid for producing the pumping vapor, means in closely-spaced relation above the level of said liquid for associating the vapor passages with predetermined portions of the surface of the liquid in the boiler and supporting a plurality of depending baffles adapted to impede migration of pumping vapors along the surface of said liquid, means for returning condensed liquid to the outer portion of the boiler and means in said boiler for controlling the flow of liquid from the outer portion to the inner portion of the boiler.

3. A diffusion pump comprising a plurality of pumping jets, a condensing surface for said jets, a common boiler, a mixture of vaporizable liquids in said boiler, means below the normal surface of said liquid to provide a plurality of liquid-retaining cells, a chimney for each of said jets, one of said chimneys extending in proximity to and terminating above the normal surface of said liquids and supporting a plurality of depending baffles adapted to impede migration of pumping vapors between said chimneys and means for returning the condensate to a predetermined portion of said liquid-retaining cells

and openings for restricting liquid flow from said receiving cells to the remaining cells.

4. A diffusion pump comprising a pump chamber, a plurality of serially operating pumping jets in said chamber, a common boiler for all of said jets, vapor chimneys for each of said jets, a condensing surface for condensing the vapor passing through said jets, means for returning the condensate to a predetermined portion of said boiler, one of said chimneys extending in proximity to the surface of a liquid in said boiler, baffle means for restricting vapor flow between said chimneys, and baffle means submerged in the liquid in said boiler for controlling the quality of the vapor evolved under the several chimneys.

5. A diffusion pump comprising a pump chamber, a plurality of serially operating pumping jets in said chamber, a common boiler for all of said jets, vapor chimneys for each of said jets, a condensing surface for condensing the vapor passing through said jets, means for returning the condensate to a predetermined portion of said boiler, one of said chimneys extending in proximity to and terminating above the surface of a liquid in said boiler, baffle means depending from one of said chimneys for restricting vapor flow between said chimneys, and baffle means submerged in the liquid in said boiler for controlling the quality of the vapor evolved under the several chimneys, said last-mentioned baffle means dividing said boiler into a plurality of cells.

6. A multi-stage diffusion pump of the self-fractionating type comprising a common boiler for all stages of the pump, means for controlling the flow of the vapor-evolving liquid in said boiler, separate chimneys for each stage of said pump, one of said chimneys extending into closely spaced relation to and terminating above the surface of the liquid in said boiler and baffle means depending from one of said chimneys for impeding the flow of vapor from one chimney to another.

7. A self-fractionating oil-diffusion pump comprising a low-pressure jet, a high-pressure jet, a common boiler for both said jets, a quantity of oil in said boiler, a condenser cooperating with both said jets, means for returning condensate from said condenser to the outer portion of the boiler, means for impeding the flow of oil from the outer portion of the boiler to an inner portion for vaporizing the more volatile portions of the oil near the outer portion of the boiler, baffle means in the space above the surface of the oil in the boiler for impeding intermingling of the vapors generated in the outer and inner portions of the boiler, a vapor passage for conducting the vapors from the outer portion of the boiler to the high-pressure jet and a passage for conducting the vapors generated in the inner portion of the boiler to the low-pressure jet.
